UNITED STATES PATENT OFFICE.

FRANK A. WELLS, OF NEW YORK, N. Y.

DESIGN FOR A BATH-TUB.

SPECIFICATION forming part of Design No. 32,859, dated June 19, 1900.

Application filed May 25, 1900. Serial No. 18,008. Term of patent 7 years.

To all whom it may concern:

Be it known that I, FRANK A. WELLS, a citizen of the United States, and a resident of New York city, borough of Manhattan, New York, have invented and produced a new and original Design for Bath-Tubs, of which the following is a specification, reference being had to the accompanying drawings, forming part hereof, wherein—

Figure 1 is a side elevation of a bath-tub embodying my design, and Fig. 2 is a transverse section thereof.

The essential feature of my design consists in a bath-tub having a flaring rim at its open top, below which the outer surface is curved inwardly and outwardly in ogee form, and at the corners are pedestals.

In the drawings the bath-tub is indicated

by the letter A, the flaring rim by the letter a, the inwardly-curved surface by the letter b, and the surface below the latter, which is curved outwardly or convexly, is denoted by the letter c, and this surface is extended under to the bottom d. The rim a and the curved surfaces b c extend symmetrically around the hub, and the general surface contour is substantially in ogee form vertically. At the corners the tub has pedestals e.

What I claim is—

The design for a bath-tub, substantially as herein shown and described.

FRANK A. WELLS.
